AUTOMATIC CONVERSION IMMERSING MACHINE

Willard J. Harper, Middletown, Paul A. Hauck, Union, and Martvig J. Moll and Donald G. Dutcher, Fair Haven, N.J., assignors to Hanson-Van Winkle-Munning Co., Matawan, N.J., a corporation of New Jersey

Filed Dec. 29, 1958, Ser. No. 783,591
31 Claims. (Cl. 198—19)

The present invention relates to Automatic Conversion Coating Machine and has for an object to provide a mechanism designed to function specifically with one work load that performs a wide range of operational requirements, namely:

Any treatment cycle, where metal parts or any materials require a sequence of different processing baths to prepare the work for a specific purpose, such as cleaning to remove dirt, grease, etc., paint preparation, oxide or phosphate coatings, blackening of metal surfaces, pickling of work surfaces, plating, anodizing, dye or dip treatments, where the treatment in each bath is individually controlled and the entire mechanism fully automatic.

Another object of the invention is to provide a mechanism where the treatment timing in each bath may be set or varied without disturbing the functional operation of other set treatments in the process cycle, where these variables can be preset differently for each new batch to compensate for processing characteristics of each new batch, where the work load can skip a specific vat or a series of vats by an intelligence that cycles and controls this single functional load of the machine, where this intelligence can be made to repeat several operations in a back and forth shuttle arrangement before proceeding to other required treatments for a specific process requirement, where this one load can be received at one end, discharged at the other end by automatic methods, or designed to shuttle the load back at a high speed to discharge at the same end as loading, and where the load may be a rotating barrel, basket, tray, tipping work crate, a rack of work or a single large piece.

A further object of the invention is to provide a machine wherein the rotating work carrier, where it is a barrel, cylinder or other form of receptacle may be varied in speed to suit each specific treatment tank, reverse rotation, stop, start rotation, all at the will of a control intelligence designed to provide the variables necessary for different processing baths, i.e.

(A) Cleaning for removal of dirt at high revolutions per minute.

(B) Deburring, where different speeds are required, depending on specific baths, deburring compounds, shapes and conditions of parts, solutions, density and composition.

(C) Salt bath treatments with subsequent cleaning cycle, drying, etc.

(D) Fluxing and galvanizing where a work load may turn, pass through a top blanket in the kettle and operations peculiar to hot galvanizing, tinning, etc., where a control intelligence can perform many functions on the one operating work load of the machine.

(E) Very slow speeds to prepare a soft conversion coating on the metal parts or materials, where the higher speeds in prior treatments would rub off the coating as rapidly as applied, i.e., blackening, phosphating, blueing of metal surfaces, etc.

A still further object of the invention is to provide a

2

mechanism for the metering of a defined work load, either in quantity, volume or weight, an automatic means of dumping or transferring the work load to a cylinder or container where a cover is used to prevent spillage during processing, an automatic device to close and lock the cover, subsequent cycle processing in any of the methods indicated previously in the immediately preceding paragraph, and an automatic device to open the cover at the opposite end of the cycle to spill or discharge the load to a receptacle, belt, hopper or other receiving bucket or conveyor device, where the load then receives other manufacturing or assembling operations, all such sequences being performed automatically with this single work load machine.

10 15 The invention has for a further purpose to produce an automatic conversion coating machine having unique features bringing important advantages in process flexibility, work adaptability and labor savings.

For purposes of illustration the invention is shown in a 20 straight-line machine having a loading station at one end and an unloading station at the other end and with a barrel type receptacle for processing small parts like spark plugs, nuts, screws, pins, etc.

With the foregoing and other objects in view, the 25 invention will be more fully described hereinafter, and will be more particularly pointed out in the claims appended hereto.

In the drawings, wherein like symbols refer to like or 30 corresponding parts throughout the several views.

FIGURE 1 is a side elevational view with parts of the 35 main framework and tanks or vats broken away and shown in section and with the elevator and barrel receptacle carried thereby shown in full lines in elevated position and in dotted lines in lowered position, all of a form of machine constructed in accordance with the present invention.

FIGURE 2 is a side elevational view of the machine with the elevator in elevated position and the barrel receptacle at the Load Station.

40 FIGURE 3 is a top plan view of the machine with the barrel receptacle at the Load Station and in dotted positions at an intermediate tank station and at the Unload Station.

45 FIGURE 4 is an end elevational view of the machine taken from the right-hand end of FIGURE 1.

FIGURE 5 is a vertical transverse sectional view taken on the line 5—5 of FIGURE 1.

50 FIGURE 6 is an isometric view of the machine taken from the Load Station with the cover of the barrel receptacle open to receive a load.

FIGURE 6A is a fragmentary isometric view taken on an enlarged scale of a portion of the barrel receptacle and cover showing a form of yieldable detent for holding the cover in open or closed positions.

55 FIGURE 7 is also an isometric view being a blow-up of the Load Station end of the machine similar to FIGURE 6 but with parts greatly magnified for clarification.

FIGURE 8 is a vertical transverse sectional view taken on the line 8—8 in FIGURE 9 through the work carrier carriage on an enlarged scale.

60 FIGURE 9 is an end elevational view taken on a smaller scale looking from the left of FIGURE 8 at the drive end of the barrel receptacle.

FIGURE 10 is an edge elevational view of a form of 65 trip device and limit switch which may be used at the Load Station and showing a fragment of one of the paddle arms engaging the stop member.

FIGURE 11 is a front elevational view of the same with parts broken away and parts shown in section.

FIGURES 12, 13 and 14 are diagrammatic sequence views showing relative positions of the barrel receptacle and cover at the Load Station.

FIGURES 15, 16 and 17 are similar views of the barrel receptacle and cover at the Unload Station.

FIGURES 18^a and 18^b together comprise an electrical schematic of the drive and control circuits, showing one arrangement thereof as applied to the mechanism illustrated in the foregoing figures of the drawings.

FIGURE 19 is a schematic of a form of operating cycle illustrating one manner of use of the invention.

FIGURE 20 is a fragmentary top plan view of a form of circular or loop machine showing an application of the invention thereto.

FIGURE 21 is an elevational view of the cylinder or receptacle illustrating a modified form of cover closing mechanism at the Load Station.

FIGURES 22, 23 and 24 are end elevational views at the Load Station of the cover closing mechanism illustrated in FIGURE 21 and showing progressive views of the movements of the cylinder and cover closing mechanism.

FIGURES 25, 26 and 27 are also end elevational views of the cylinder at the Unload Station showing the mechanism for opening the discharge opening.

FIGURE 28 as a fragmentary elevational view of the cylinder illustrating a still further modified form of cover closing mechanism at the Load Station.

FIGURES 29, 30 and 31 are end elevational views showing in phase the action of the form of cover closing mechanism illustrated in FIGURE 28.

FIGURES 32 and 33 are end elevational views of the cylinder at the Unload Station showing a form of the invention for uncovering the discharge opening.

FIGURE 34 at the Load Station is a fragmentary elevational view of the cylinder showing a still further modified form of cover closing mechanism.

FIGURES 35 and 36 are end elevational views of the same showing the cover in the open and subsequently in the closed position.

FIGURES 37 and 38 are end elevational views of a form of cover opening mechanism at the Unload Station similar to that at the Load Station.

FIGURE 39 is a top plane view of a still further modified form of cover closing mechanism at the Load Station.

FIGURE 40 is an elevational view of the same taken from one end thereof.

FIGURE 41 is a side elevational view of the same with the parts in the position of FIGURE 39 with the cover open.

FIGURE 42 is a view similar to 41 but with the parts in a subsequent position and the cover closed.

FIGURE 43 is a similar end elevational view at the Unload Station of a similar mechanism for effecting opening of the cover with the opening in the down discharge position.

FIGURE 44 is a similar view showing the parts in a subsequent position of movement.

FIGURE 45 is a fragmentary elevational view of a still further modified form of cover closing mechanism at the Load Station.

FIGURES 46 and 47 are end elevational views of the same with the cover respectively in the open and the closed positions.

FIGURES 48 and 49 show end elevational views of the cylinder at the Unload Station showing similar mechanism for effecting the opening of the discharge opening in the lower position of the latter.

FIGURE 50 is a fragmentary isometric view of a modified form of the device in which application of the invention is made to a closed loop form of machine wherein a plurality of load carriers are or may be em-

ployed and showing a cylinder carrier at the Unload Station in an initial position of its approach.

FIGURES 51 and 52 are also fragmentary isometric views showing the successive movements of the mechanism.

FIGURE 53 is an isometric view with parts shown in section of the cover opening and conveyance stop mechanism.

FIGURE 54 is a fragmentary isometric view of a modified form of the cylinder and rotary drive mechanism.

FIGURE 55 is an isometric view with parts broken away of a form of mechanism at the Load Station for checking horizontal movement of the cylinder, closing the cover after charging, subsequently arresting rotation and in time restoring horizontal conveying movement and incidental rotation of the cylinder.

FIGURES 56, 57 and 58 are fragmentary phase views of the mechanism of FIGURE 55 showing the same in various positions in association with the cover actuating lever of the cylinder.

FIGURE 59 is an isometric view of the form of device shown in FIGURES 56-58 with parts broken away.

FIGURE 60 is a plan view showing the main lever swung forwardly to permit the cover arm to pass.

FIGURE 61 is a similar plan view showing the main and supplemental lever swung rearwardly to actuate the limit switch.

Main Frame and Vats

Referring more particularly to the drawings, 50, 52, 54, 56 and 58 designate tanks or vats disposed in a pre-arranged order or a sequence and containing liquid solutions of varying compositions for the treatment of articles contained in a work carrier movable from a Load Station, so designated in the drawings, to an Unload Station, also so designated in the drawings.

In FIGURE 1, the load carrier is represented as a barrel receptacle 108, illustrated in full lines at the Load Station, in dotted lines at an intermediate point of traverse from the Load Station to the Unload Station where the carrier or barrel receptacle has been lowered to immerse the same in the bath contained in the tank 54, and again in dotted lines at the Unload Station where the treated articles are discharged from the work carrier and the work carrier is returned to the original position or to the Load Station for a subsequent charge of articles; thereafter passing automatically through the same cycle or through the cycle for which the operation has been preset.

A main frame 60 extends above the line of the tanks and may be supported by corner posts 62.

Elevator Frame and Drive

The main frame 60 is a stationary structure suitably braced and of sufficient stability to support therein the elevator frame 64 which moves up and down from the elevated main frame 60 down to the position shown in dotted lines in FIGURE 1 in which its lowers the work carrier into an immersed position within a tank or vat.

In the embodiment of the invention illustrated in the drawings the elevator frame 64 is supported from the main frame 60 on cables 66, the points of attachment being designated at 68. The cables 66 are rove over sheaves 70 suitably journaled in the main frame 60 at the four corners thereof. At the Load Station end of the main frame 60, the sheaves are supported on a shaft 72 and at the Unload Station on a shaft 74. A drive mechanism for the sheaves 70 is conveniently connected to the shaft 74 (FIG. 3), such mechanism being a chain

and sprocket drive 76 from a reduction gear 78 driven by an electric motor 80 installed upon the main frame 60. As the cables 66 are crossed between the sheaves on the two shafts 72, 74, the drive mechanism will drive both pairs of sheaves 70 and thus simultaneously pay out all cables for the lowering of the elevator frame 64 from

75

the full to the dotted line position of FIGURE 1 and for the simultaneous winding of all cables on the sheaves to raise the elevator frame by which the work carrier is raised from its position of immersion in any given vat to the traverse level above the line of tanks where the work carrier may resume its horizontal travel clear of the tank walls or barriers which separate the various treatment solutions.

Work Support Carriage and Drive

As best seen in FIGURE 8, 82 represents the work supporting carriage which is supported for horizontal movement by rollers 84 on tracks 86 mounted in the elevator frame 64. The carriage 82 also carries side thrust rollers 88 which engage against inner webs of chain guide channel beams 90 also mounted on the elevator frame 64, and through which move in a substantially horizontal direction up and down the line of tanks carriage driving chains 92 which are engaged by couplings 94 connected to the carriage 82 by which the carriage is drawn along by the chains and rolls over the tracks 86 from one tank bath station to the next. The chains 92 are trained over sprockets 96 (FIGS. 1 and 6), such sprockets 96 being affixed to shafts 98 and 100 journaled in the elevator frame 64. The shaft 100 is connected through a reduction gear 102 and a chain and sprocket drive 104 to an electric motor 106 installed on the elevator frame 64 (FIGS. 1, 2 and 3).

Work Carrier and Mounting

The single work carrier 108, as heretofore stated, in the instance illustrated herein, is in the form of a cylinder, barrel or other tubular form of receptacle having a foraminous, reticulated or otherwise apertured side tubular wall 110 affixed to end heads 112, 114, with a load and discharge opening 116 in the side wall 110. At the opposite sides of the opening 116 are stops 118, 120 disposed in the path of a stop 124 on an arcuate or other cover 122 which also may be apertured to match the receptacle 108. The cover 122 is slidably mounted in the receptacle, either within or without the side tubular wall 110 and may be supported for relatively slidable movement with reference to the side receptacle wall 110 as by side segmental plates 126 (FIGURES 8-17).

As shown more particularly in FIGURE 8, these side plates 126 are pinned or otherwise affixed to hollow trunnions 128 which are supported upon and relatively rotatable with respect to hollow trunnions 130 affixed to the end heads 112, 114 of the work carrier. The hollow trunnions 130 are mounted in bearing sleeves 132 carried by bearings 134 supported on the bottom of hangers 136 which depend from the carriage 82.

A trip paddle 138 is affixed to the hollow trunnion 128 at one end of the drum, as by a bolt 140 and nut 142 so that the trip paddle 138 is affixed to the segmental side plates 126 and to the cover 122 while the cover and the drum or barrel receptacle may be rotated independently of one another by virtue of the hollow trunnions 128 and 130.

The trip paddle may include a long arm 144 having a laterally extending finger 146 and a short arm 148 having a laterally extending finger 150. The arms 144, 148 are displaced angularly as indicated in FIGURES 12-17, this being representative of only one angular disposition which has been that adopted in practice.

Work Carrier Drive

As appears most clearly in FIGURES 8 and 9, at one end of the receptacle a sprocket 152 is affixed to the hollow trunnion 130 and driven by a chain 154 from a sprocket 156 on a reduction gear 158 driven by an electric or other motor 160, the reduction gear 158 and motor 160 being mounted in the carriage 82.

Work Carrier Cover Latch

Referring more particularly to FIGURE 6A, a form of

latch is illustrated for holding the cover 122 in both closed and open positions. A detent spring 162 of flat elastic stock is mounted as to its central portion upon a support block 164 which may be attached by screws or other fastenings 166 to the end head 112 of the barrel receptacle. A clamp plate 168 is laid over the spring 162 above the block 164 and is affixed to the block 164 as by bolts or other fastenings 170 which also pass through the central area of the spring 162.

The spring 162 extends beyond the block 164 in both directions and has free crimped ends 172 and 174 comprising inner sections 176 and outer sections 178 inclined reversely and biased to the radially outward full line position shown at 174. These sections 176 and 178 cooperate with a detent pin 180 welded or otherwise secured to the cover 122 or to the stop 124 thereof.

At the right-hand end of FIGURE 6A, the detent 180 is shown as engaged against the stop strip 120 of the barrel receptacle 110 in the fully open position of the cover 122.

In this position the detent pin 180 is blocked by the spring end 174 and in its opening movement the cover will have to be subjected to considerable force sufficient to overcome the load of the spring arm 174 as the detent pin 180 must ride up the inclined surface 178 depressing the spring arm 174 so as to permit the passage of the pin 180 in its arcuate path incident to closing movement of the cover 122 and the movement of its stop 124 over against the stop 118 of the barrel receptacle. In moving toward its closed position at the left-hand end of FIGURE 6A, the detent pin 180 will encounter the section 176 of the spring arm 172 and depress the same so as to permit passage of the detent thereby and the movement of the cover 122 into the fully closed position. When the detent 180 passes the spring arm 172 the latter from its depressed position will snap outwardly into the path of the detent 180 thus yieldably retaining the cover 122 in the fully closed position.

Work Carrier Cover Closing Mechanism at Load Station

The trip paddle 138 has already been described and is shown clearly in FIGURE 7 at the Load Station where the short arm 148 and finger 150 thereof cooperate with a stop lever 182 pivoted at 184 upon a support plate 186 on the carriage 82.

As shown more particularly in FIGURES 10 and 11, a variable limit stop in the form of a screw 188 is threaded adjustably through a lug 190 on the support plate 86 with its free end arranged to be abutted by the upper end of the stop lever 182 in obedience to the trust of a coil spring 192 disposed opposite the stop screw 188 and mounted in a spring retainer and abutment 194 on the support plate 186. A pin 196 on the upper end of the lever 182 projects loosely through a hole or slot 198 in the support plate 186 and in the path of an arm 200 of a limit switch 202 carried on the opposite side of the support plate 186.

Work Carrier Cover Opening Mechanism at Unload Station

At this point reference is made more particularly to FIGURES 8, 9, 15, 16 and 17.

At the Unload Station there is a stop lever 204 pivoted at 206 upon a support plate 208 on the elevator 64. The lower end of this lever 204 is disposed beyond the reach of the finger 150 of the short arm 148 of the trip paddle

but in the path of the finger 146 on the long arm 144 as appears clearly from FIGURES 8, 9 and 16. However, the wand 222, which is offset laterally from the lever 204 (FIG. 8) depends at its lower end into the path of the finger 150 of the short paddle arm 148. As appears in FIGURE 8, the finger 146 on the long arm 144 has sufficient lateral width to encounter and operate stop lever 204 but falls short of reaching the wand 222. On the other hand, the finger 150 of the short arm 148 of the trip paddle has greater lateral width sufficient to extend into the path of the wand 222 and to actuate the same.

Viewing FIGURE 15 and the clockwise direction of movement of the barrel receptacle as indicated by the arrow, in this directional sense the finger 150 will strike the wand 222 moving it from the full to the dotted line position without having any effect on the switch 224, this being for the purpose of permitting the passage clockwise of the finger 150.

Viewing FIGURE 17 where the barrel receptacle is being driven anti-clockwise as indicated by the arrow in this figure, the finger 150 will strike the wand 222 moving it from its dotted to its full line position and actuating the limit switch 224.

General Mechanical Operation

The elevator lift motor 80, the carriage traverse motor 106 and the barrel receptacle rotating motor 160 are all reversible electric motors having conventional brakes.

In FIGURES 1 and 12 the single work carrier or barrel receptacle 108 is shown in full lines at the Load Station with the receptacle receiving opening in an upper position with the cover 122 open to receive articles to be treated through a hopper or chute 226 (FIG. 12). At the Load Station and in this position the barrel receptacle 108 or other single work load carriers is at rest both with respect to rotation and motion of translation. The mechanism for delivering the articles to the barrel receptacle at the Load Station may itself be fully automatic (not shown) and automated with the control mechanism for the machine of this invention to the end that when the barrel receptacle 108 arrives at the Load Station it will remain there for a suitable interval of time calculated to receive a full load through the loading mechanism 226 which will be correspondingly timed to open and close the delivery of articles comprising a calculated full load. Thereupon the receptacle rotating motor 160 will be automatically energized to rotate the receptacle for the purpose of closing the cover 122 as hereinafter described. Upon completion of the closing of the cover 122, the carriage traverse motor 106 will become automatically energized to start the traverse or motion of translation movement of the work carrier 108 down the line of the tanks.

Viewing FIGURE 12, it will be seen that the barrel receptacle is rotated counterclockwise to close the cover 122 as indicated by the arrow. In a preferred mode of operation the cylinder does not rotate in its raised position while moving down the line of tanks but at each tank or treatment station as well as at the Load and Unload Stations limit switches on the elevator are positioned to be encountered by the carriage of the cylinder for controlling the starting of cylinder rotation as it is desired to tumble the articles in the cylinder when immersed in the baths. If any of the tank timers are set for treatments at any of the tanks the non-rotary cylinder will be stopped at those stations, lowered, immersed and put into rotation.

When the cylinder is rotated it receives a rotary movement about an axis which is transverse to the line of traversing movement of the receptacle down the line of tanks. In other words, the direction of rotation of the work load carrier 108 is in the line of its traversing movement. Barrel receptacles are longer axially than they are diametrically and accordingly the disposition of the axis transversely of the line of treatment tanks or stations enables shortening of the over-all length of the machine with considerable savings in construction material, volumes of solution liquids in the vats, shorter runs of the work carrier, and other advantages, all of which effect savings in labor costs and processing time.

Moreover, in those baths in which the immersed work carrier has a motion of traverse while immersed, the direction of rotation of the apertured cylindrical wall of the work carrier is conducive to a better and more complete contact of the solution with all surfaces of the articles being tumbled in the barrel receptacle.

As the work carrier 108 arrives over any of the vats or treatment stations, it may be lowered by energizing the

75 elevator lift motor 80 to pay out the cables 66 and allow a gravity descent of the elevator 64, the lowered position of which is shown in dotted lines in FIGURE 1 with the work carrier 108 immersed in the solution contained in the vat 54. During descent of the elevator 64, the carriage traverse motor 106 is de-energized and preferably braked but the barrel receptacle rotating motor 160 is put in operation to rotate the barrel receptacle while in its lowered immersed position.

The brake associated with the elevator lift motor 80 may simply be released to permit the elevator 64 in its elevated position to drop down to the lowered immersing position. The elevator lift motor 80 may be energized when effecting a lift of the elevator 64 from its lower to its upper position, in which latter position the work load carrier 108 is in its correct level for resuming its traversing movement from treatment station to treatment station progressing toward the Unload Station.

The arrangement is such that the work load carrier 108 20 may be caused to skip some treatment stations and also to move reversely backward or toward the Load Station to reverse sequences of treatment from the order in which the baths have been laid out in the line.

When the full treatment cycle is completed, the work 25 carrier 108 arrives at the Unload Station. Here the opening 116 in the barrel receptacle is rotated to a down dump position as indicated in FIGURE 16 and after discharging the articles treated the direction of rotation of the barrel 30 receptacle is reversed (FIG. 17) to bring the opening 116 to the upper load position, in which position the barrel receptacle is then moved back to load position by action of the carriage traverse motor 106.

It will of course be understood that the Load and Unload Stations may be consolidated and that when the 35 barrel receptacle has completed its traverse of the full treatment cycle, instead of being unloaded at the Unload Station at the right end of the machine as illustrated in FIGURE 1, the unload controls may also be located at the Load Station and the load carrier may be simply returned to the Load Station and there be subject to the same controls for dumping the load and restoring the opening in the barrel receptacle to an upper position suitable for receiving the new load at the Load Station.

When a barrel receptacle is used in small-part processing, it can be rotated continuously, intermittently, or not at all—in each tank, during each transfer, and at the unloading point, with simple control settings. Easy adjustments permit same-end loading and unloading. With this feature, the machine adapts readily to many cycle variations.

The overall design of the machine is quite simple. The only moving parts are the elevator framework, which extends substantially the length of the machine, and the suspended or barreled work load. The elevator framework 55 contains chain and drive for station-to-station travel and return. The elevator is raised and lowered by an independent drive. Trip cycles and immersion periods are determined by pre-set contacts switches and timers located at each station.

Cover Opening and Unloading Operation

FIGURE 15 shows the barrel receptacle as it arrives at the Unload Station with the cover 122 closed and the position of the cover variable. The barrel is rotating clockwise. As the stop lever 204 is outside the radial range of movement of the short arm 148 and its finger 150 of the trip paddle, such finger will pass beneath the lever 204. It will engage the wand 222 but simply to move it out of the way to the dotted line position without tripping the switch 224. Meantime the long arm 144 has been rotating around and eventually the finger 146 thereof will arrive against the stop lever 204 in substantially the position shown in FIGURE 16. As the load of the spring 212 which holds the lever 204 against its stop 210 exceeds the load value of the spring detent (FIG. 6A)

which holds the cover 122 yieldably closed, the arm 144 and its entrained cover 122 will be arrested in rotation while the barrel continues to rotate clockwise, causing the stop 118 to move away from the now stationary stop 124 of the cover 122 thus uncovering the opening 116 in the down position favorable for dumping the contents of the barrel into a suitable receptacle or conveyor. When the barrel stop 120 arrives against the now stalled cover stop 124, the cover 121 and the trip paddle including the long arm 144 will be forcibly required by the drum rotating mechanism to become entrained with the drum and to resume rotation therewith, the finger 146 bearing against the stop lever 204 now exerting sufficient thrust to overcome the load of the spring 212, thus moving the upper portion of the lever 204 off its stop 210, compressing the spring 212 and moving the pin 216 against the arm 218 of the limit switch 220, tripping such limit switch which thereupon opens the circuit of barrel receptacle rotating motor 160 and suspends the rotation of the barrel. Moreover this limit switch 220 also starts unload time delay and as soon as the timer times out the cylinder will be caused to rotate in the direction of the arrow as appears in FIGURE 17. In so doing the uncovered opening 116 is rotated around to an upper position. In other words, to the loading position and simultaneously therewith the finger 150 on the short arm 148 displaces the wand 222 and actuates the limit switch 224 to thereupon interrupt the circuit to the barrel receptacle rotating motor 160 to retain the barrel receptacle in the angular position revealed in FIGURE 17, in which position it is moved on a return traverse on reverse operation of the carriage traverse motor 106 back to the Load Station, where the barrel arrives in the position of FIGURE 12 with the uncovered opening 116 registering with the chute or hopper 226. Simultaneously with this arrival, the filling mechanism will deliver a charge of articles to the barrel, the cover will be automatically closed and a preselected pattern of cyclic treatment resumed.

Loading and Cover Closing Operation

While at the Unload Station both arms 144 and 148 of the trip paddle perform functional operations, at the Load Station only the short arm 148 is functional. As a matter of fact, the drum 108 arrives in the position of FIGURE 12 at the Load Station in non-rotary condition with the cover 122 and short arm 148 in the positions predisposed as illustrated in FIGURE 17 at the Unload Station. The barrel arrives in FIGURE 12 from the right moving toward the left so that the finger 150 moves up against the stop lever 182. As the load of the spring 192 exceeds the load of the detent spring holding the cover 122 in the open position, the short arm 148 and its entrained cover 122 will remain stationary while the barrel rotating motor 160 is energized in reverse direction to drive the barrel counter-clockwise, this movement continuing until the barrel stop 118 impinges against the cover stop 124 at which time the cover 122 will be entrained to move with the barrel due to the superior force of the motor 160 over the load of spring 192. The finger 150 will thereupon shift the lever 182 so that the spring 192 will be compressed and the wand 200 actuated to trip the limit switch 202. This action momentarily suspends motor 160 rotation of barrel and also energizes carriage traverse motor 106 to move the barrel to the right from FIGURE 13 thus withdrawing finger 150 from stop lever 182. The motor 160 may be thereupon or later re-energized so as to rotate the barrel anti-clockwise in the direction of the arrow in FIGURE 14 which is its normal direction of rotation. The barrel then moves away from the Load Station and transfers to the first treatment tank.

It will be understood that where electroplating operations are involved there will be anodic bodies placed in the indicated tanks and dangler or other cathodic bodies

placed in the barrel receptacle, which is well known in the prior art (Patent 2,249,609, granted July 15, 1941).

It will also be understood that the means for opening and closing the cover of the barrel may be used in forms of machines other than the single straight line machine illustrated in the drawings, and the barrel and its cover operating mechanism may also be employed in multiple work carrier machines and loop type machines.

The Circuitry

Referring now to FIGURES 18^a and 18^b there is shown a three-phase, 440 volt, 60 cycle supply for driving the elevator motor, the conveyor motor and the cylinder drive motor. Each of these motors are subjected to the controls of a secondary circuit. Coming off the 440 volt supply between the motors and fuses is connected a control transformer having its primary connected across the 440 volt supply and being provided with a secondary for supplying electrical energy to the secondary or control circuits for the motors.

With the main power switch A off, all latch relays are checked to see that they are not latched in their up position. The starter re-set buttons are checked as are the brake control fuses. All of the timers are set as desired for carrying out the particular cycle of the machine, for instance, to effect the cycle shown in FIGURE 19. For example, the timer in the No. 1 tank is set for one minute, 30 seconds; the timer for the No. 2 tank is set for 30 seconds; the timer for the No. 3 tank is set for 12 minutes; the No. 4 tank is set for 30 seconds, and the No. 5 tank timer is set for 30 seconds. The air dry timer is set for 48 seconds, and the unload timer for 45 seconds.

The cabinet door for the timer cabinet is then secured; the automatic-manual selector switch B is turned to the manual position; the main power switch is turned to the "on" position; the red light, indicating manual, will come on and the two green lights for the elevator and conveyor brake controls will come on.

By use of the jog buttons C, the elevator may be jogged to the "up" position. Depressing and holding any one of the jog buttons D, E, F, G and H will cause the desired motion in the particular circuit in which the jog button is placed until either the button is released or the maximum limit of travel is attained. For instance, it is not possible to jog the elevator down at either the load or unload station. The jog button E is then held in and the conveyor will be moved in a forward direction to the unload station. Upon arrival of the cylinder 108 at the unload station, the machine is now ready to go into automatic operation. The automatic manual selector switch B is then turned to the automatic position. The red manual light will go out. The cycle start button I is then pressed and released. The green light indicating automatic will come on.

At the lower left-hand portion of FIGURE 18^a the cycle start switch I is located. When this switch is closed the automatic control relay J is energized which will close all normally open A.C. contacts and open all normally closed A.C. contacts. This being the case current will pass from line 1 through the closed unload position limit switch (UPLS) which has been closed by virtue of the unit being at the unload station at the commencement of automatic operation. The current will then pass through the closed A.C. contacts, the normally closed 2LR, when 1LR, the normally closed LCOLS, through the cylinder drive reverse contacts down through the cylinder drive and to the return line 2. This causes the cylinder 108 to rotate in the direction shown in FIGURE 15. This rotation of cylinder 108 continues until, as shown in FIGURE 16, the arm 144 causes opening of LCOLS just above the cycle start button in FIGURE 18^b which will cause LCOLS to open and de-energize the cylinder drive, at which time the contact of LCO, which has been open previously, will close thereby cut-

ting the LCO time delay relay in the circuit which will maintain the cylinder 108 in the discharge position shown in FIGURE 16 for the requisite time to discharge the contents thereof.

When the LCOTD times out, it in turns energizes 1LR which causes the cylinder drive to rotate in the forward direction until the arm 148 actuates the wand 222 of the one-way LCPLS which positions the cylinder cover opening in a position to receive the next load. When LCPLS is actuated, the cylinder drive stops and 2LR is energized. This in turn releases 1LR. The conveyor motor is energized and rotates in a reverse direction moving the cylinder 108 toward the load station. Upon arrival of the cylinder 108 at the load station, the load position limit switch (LPLS) is actuated causing the conveyor motor to cease rotation and stop the conveyor. This will supply a signal indicating that the cylinder is ready to load.

When re-loading is complete a signal to that effect will be applied across terminals 25, 26 (FIGURE 18^b). This signal energizes loaded LR closing the contacts between the terminals 25 and 29 and through closed LCC the cylinder drive circuit will be energized in a forward direction of rotation to close the cylinder cover. When the cover is closed, as shown in FIGURE 13, LCCLS is actuated which opens the circuit to the cylinder drive motor, stopping the same and energizes the load cover closed latch relay LCC. This in turn releases loaded LR. The conveyor starts forward arriving at the No. 1 tank position where it engages the No. 1 TPLS and stops. LCCLR is released at this time; the elevator starts down and contacts the elevator down limit switch EDLS, thereby stopping the elevator motor and simultaneously applying the brake thereto. This energizes the 1CR relay which places the No. 1 timer in operation and when the No. 1 timer times out, the normally open No. 1 timer closes (upper right-hand end FIGURE 18^a) thereby energizing the elevator up circuit which causes the elevator to start up, lifting the cylinder 108 from the No. 1 tank. The elevator continues to raise until the elevator hits the elevator up limit switch EULS which opens the elevator motor circuit, stopping the same. Upon opening of the elevator up circuit, the conveyor forward circuit is energized and advances the conveyor until the No. 2 tank position limit switch (No. 2 TPLS) is closed which stops the conveyor and energizes the elevator down circuit. All tank timers are the reverse clutch type timer.

This cycle keeps repeating until the cylinder 108 has completed its immersion in the No. 5 tank and the No. 5 timer has timed out. When this has occurred, the elevator up circuit is energized and the elevator starts up until it engages EULS, at which time the drain timer is placed in circuit with the conveyor motor and the cylinder remains over the No. 5 tank for the period determined by the drain timer. When the drain timer has timed out, the conveyor motor is energized in a forward direction and moves the cylinder 108 until the unload position limit switch is actuated, at which time the conveyor motor is de-energized, its brake applied and the above-described cycle is repeated which consists in dumping the cylinder and then returning the cylinder to the load station for commencement of another cycle.

FIGURE 19 Schematic Example

As shown in FIGURE 19, the machine illustrated will operate in accordance with the circuitry of FIGURES 18^a and 18^b to perform the following automatic cycle. Reference is also to be had to FIGURE 1.

From actuation of the machine at the load station the cylinder will proceed along the conveyor for a 45 second interval, at which time it will enter the tank 50, taking a 7 second interval to become immersed in the tank where it will remain for a period of one minute and 30 seconds, the time interval pre-set in the tank 50 timer, at the conclusion of which it will take 7 seconds to elevate from

the tank. The cylinder will then advance horizontally for a 7 second period to clear the partition wall between the tank 50 and tank 52. It will then descend into tank 52 taking a period of 7 seconds to become immersed and it will remain in the tank 52 for a period of 30 seconds at the conclusion of which, upon the timing out of the tank 52 timer, the cylinder will be elevated requiring a 7 second elevation and will move forward along the conveyor over the line of tanks for a period of 9 seconds to clear the partition between the tanks 52 and 54, at the conclusion of which the cylinder will then be immersed in tank 54, requiring 7 seconds to attain the prescribed depth of immersion. Upon attaining the prescribed depth, the cylinder will remain in tank 54 for a 12 minute immersion period which has been pre-set in the tank 54 timer. At the conclusion of this 12 minute immersion period the cylinder will be elevated requiring 7 seconds for elevation, at the conclusion of which the cylinder will be moved horizontally for a 9 second period and immersed in tank 56. Here again the time required to attain immersion at the prescribed level of the tank from the elevator up position is a 7 second period. It will be noted that the horizontal time period for forward motion prior to entering and after leaving tank 54 is 9 seconds rather than 7 seconds. This increase of 2 seconds is required due to the increased wall thickness of the tank 54. The cylinder will remain immersed in tank 56 for a period of 30 seconds and when tank 56 timer has timed out, the cylinder will be elevated for further horizontal travel to clear the partition between tanks 56 and 58. Upon completion of this 7 second horizontal travel, the cylinder will then be immersed in tank 58 requiring a descent period of 7 seconds and it will remain in tank 58 for 30 seconds, the time pre-set in tank 58 timer. When the tank 58 timer has timed out the cylinder will be elevated clear of the tank, requiring 7 seconds to become elevated and it will remain in the elevated position for a period of 48 seconds during which time the contents of the receptacle cylinder are air dried. The timer for the air drying period is also shown in the electrical schematic as the drain time, FIGURE 18^a. Upon timing out of the drain timer the cylinder will be advanced horizontally for a 7 second period at the conclusion of which it will enter a 45 second unload cycle. Upon completion of the unload cycle timing out, the cylinder will then be returned to the load station which is a reverse horizontal drive of the cylinder in the elevated position opposite in direction to its just completed cycle of travel which will take 46 seconds to accomplish.

While this cycle in FIGURE 19 is for one application of this machine, namely, phosphating or coating articles, it is merely representative of but one cycle of which this machine is capable of performing. By varying the solutions of the tanks, the articles to be coated, the time periods will of necessity vary with the treatment to be employed and to those skilled in the art it will be appreciated that the timers of the various tanks can be set to give different time periods of immersion duration than those shown in FIGURE 19.

Modified Cover Closing Mechanism FIGURES 20-27, Inclusive

Referring more particularly to FIGURE 20, 230 designates a loop form of mechanism in which the cylinder or barrel 108 travels around in the direction of the arrows from Load Station, so designated in FIGURE 20 around to the left and then reversely in the other leg of the loop up to the Unload Station. After unloading the barrel traverses the curved end 232 of the loop and shortly arrives at the Load Station.

FIGURES 21 to 24, inclusive show the mechanism and the phases of movement at the Load Station.

The cylinder or barrel 108 may arrive, as indicated in FIGURE 22, at the Load Station with the opening 116 uncovered whereby material to be processed may be de-

livered to the cylinder 108 through the chute or hopper 226^a.

The trip paddle 138^a in this instance is in the form of a bar or cover operating arm which is affixed to the shaft 128 to which the side plates 126 of the cover 122 are affixed.

The cylinder 108 moves from the left toward the right into the position of FIGURE 22 with the trip member 138^a bringing up against a pin 236 on an arrester arm 234 which is pivoted at 238 to a lug 240 on the elevator at the Load Station. The arrester arm 234 is biased to the upright position of FIGURE 22 by a coil spring 242 which will maintain the arm 138^a in the upright position with the cover 122 motionless during rotation of the cylinder 108 in the direction of the arrow until the stop 118 of the cylinder engages the stop 124 of the cover 122 whereupon the cover 122 will be entrained for movement with the cylinder 108 and in so doing will entrain the arm 138^a to move from the position of FIGURE 23 to that of FIGURE 24 overcoming the load of the spring 242 in so doing and moving the arrester arm 234 to an inclined position sufficient to trip the limit switch LCCLS. This pivotal movement of the arrester arm 234 permits the cover bar 138^a to pass to the right with the cylinder 108 and thus to move on down the line of treatment tanks in the Load Station section of the loop.

When the cylinder completes the circuit around to the Unload Station, as shown in FIGURE 25 the cylinder 108 will move from right to left so that the cover bar 138^a will bring up against the pin 246 of an arrester arm 244 which is pivoted at 248 to a lug 250 at the Unload Station. The arrester arm 244 is under the load of a spring 252. Thus the cover 122 will be held motionless while the cylinder 108 rotates clockwise in the direction of the arrow thus moving the opening 116 away from the cover 122 to the down position shown in FIGURE 26 favorable for the discharge of the treated articles. In the fully open position of the cover 122 the cover and cylinder stops will entrain the cover to thereupon move in rotation with the cylinder and the cover bar 138^a will be compelled to rotate accordingly, which movement is permitted by the expansion of the spring 252 and the movement of the arrester arm 244 over to the inclined position of FIGURE 27. When the arm 138^a passes the pin 206, the spring 122 restores the arrester arm 244 to the vertical position of FIGURES 25 and 26 in readiness for the return of the cylinder or to receive a successive cylinder. As shown in FIGURE 27, incident to the movement of the arrester arm 244, the limit switch LCCLS will be tripped. As shown in FIGURE 27, the cylinder 108, after dumping, may be rotated in the direction of the arrow to bring the opening 116 to an upper position as shown in FIGURE 22 for subsequent re-filling at the Load Station.

*Pneumatic or Hydraulic Cylinder Cover Actuation
FIGURES 28-33*

In this form of the invention, the cover 122 is moved back and forth relatively to a stopped cylinder 108 in order to open and close the opening 116.

As shown, a cover operating arm 138^b carries a vane 254 in the path of movement of a ram or plunger rod 256 of a pneumatic or hydraulic motor 258. The cylinder rotation is controlled by a limit switch and is stopped in proper loading position as shown in FIGURE 29. This limit switch may also stop the cylinder conveying mechanism in the position of FIGURE 29 with the vane 254 disposed relatively to the ram 256 so as to be actuated thereby comparatively with respect to the positions of FIGURES 29 and 30. A full stroke of the ram or plunger rod 256 will move the cover to a closed position. The parts in moving to the position of FIGURE 30 also trip a limit switch to cause resumption of the operation of the conveying motor and the cylinder rotating motor mechanism. Due to the subsequent withdrawal of the

plunger 256 into its cylinder 258 (position of FIGURE 31) the cylinder 108 and its cover actuating arm 138^b are free to move to the right or in the case of a straight line machine the cylinder may be moved forward to the various treatment stations and finally to the Unload Station as shown in FIGURES 32 and 33 where a similar mechanism may be employed to open the cover 122.

As shown in FIGURE 32, the cylinder 108 is stopped with the cover 122 closed and opening 116 in the down position, this being accomplished by suitable limit switch or the like. In this position the vane or paddle 254 is also over the ram or plunger rod 260 of the cylinder 262 of a pneumatic or hydraulic motor. By introducing pressure into the motor the ram 260 is projected to the position of FIGURE 33, the stroke being substantially equal to the angular distance required to move the cover 122 from the closed position of FIGURE 32 to the open position of FIGURE 33. The movement of the parts to the position of FIGURE 3 will also trip a limit switch which will set the cylinder 108 rotating to bring the opening 116 up to the upper load position of FIGURE 29.

After dumping the contents of the cylinder 108 as shown in FIGURE 33 and withdrawing the ram 260, the cylinder is free to proceed to left or to the right on its conveying movement through a straight line or a loop machine.

*Chain Drive Actuation of Cylinder Cover
FIGURES 34-38*

At the Load Station illustrated in FIGURES 34, 35 and 36, 264 represents a roller or projection extending out laterally from the side of a large sprocket 266 mounted on a shaft 268 in appropriate bearings on the elevator framework. A chain 270 extends about the sprocket 266 and about also a small sprocket 272 driven through a reduction gear 274 from a reversible electric motor 276.

The cylinder 108 will preferably arrive at the Load Station with the opening 116 in top position and with the cover 125 removed from the opening as shown in FIGURE 35. The rotation and conveyor movement of the cylinder 108 will be stopped in the position of 35 at the Load Station by appropriate limit switch operation. After the cylinder has been charged, the motor 276 may be energized in an appropriate direction to move the roller or projection 264 beneath the cover arm 138^c to lift the same to the position of FIGURE 36 thus closing the cover 122. Incident to this movement of the arm 138^c and by limit switch actuation the direction of rotation of the motor 276 is reversed to return the contact roller 264 to a lower starting point and also to continue the machine cycle.

At the Unload Station, there is also a roller projection 278 arranged in the path of the cover arm 138^c, which roller or projection 278 is carried by a large sprocket 280 rotating about a shaft 282 and driven by a chain 284 from a small sprocket 286 driven through a reduction gear 288 from a reversible electric motor 290.

When the cylinder 108 arrives at the position of FIGURE 37 at the Unload Station, the motor 290 is operated to bring the roller or projection 278 up beneath the cover operating arm 138^c and by continuing this movement the roller 278 and arm 138^c are elevated to the position of FIGURE 38, the same being accompanied by the shifting of the cover 122 around with respect to the stalled cylinder 108 thus uncovering the opening 116 in the dump or discharge down position. By reversing the direction of rotation of the motor 290, the roller 278 may be caused to descend to a lower origin position where it will be clear of the arm 138^c wherever the cylinder or any subsequent cylinder returns to the unload position.

*Cylinder Cover Rack and Pinion Actuation
FIGURES 39-44*

At the Load Station represented in FIGURES 39 to 42, inclusive, 292 designates a reversible electric motor driving a reduction gear 294 and therefrom a drive shaft 296 having a pinion 298 meshing with a reciprocating rack bar

300 which is mounted for movement in a frame 302. The rack bar constitutes a carriage supporting guide 304 in which a bar 306 is mounted for laterally sliding movement but entrained to move with the rack bar 300. A roller 308 on the bar 306 is adapted to be projected into the path of movement of the cover actuating arm 138^a. Upstanding from the bar 306 is a pin 310 movable back and forth with the rack bar, the pin 310 moving in a cam track 312. When the cylinder 108 reaches the Load Station it is stopped in traverse and in rotation and is filled through the opening 116 which is uncovered as appears in FIGURE 41. When the cylinder 108 has received its load the motor is actuated to drive the pinion and the rack to shift the rack bar 300 toward the right as indicated by the arrow in FIGURE 41. In this position the roller 308 pushes upon the cover actuating bar 138^a and shifts the cover 122 from the position of FIGURE 41 to that of FIGURE 42 in which the cover is completely closed. The reversal of the motor returns the rack bar carriage and in so doing swings the contact roller 308 out of position to provide clearance for the next cylinder: whereupon the cycle resumes.

In FIGURES 43 and 44, at the Unload Station, a similar mechanism is employed to open the cover 122 which is shown closed in FIGURE 43 and open in FIGURE 44 with the opening 116 disposed downwardly in the gravity discharge position of the cylinder 108. A roller 314 moves into and out of the plane of movement of the cover actuating arm 138^a, such roller being carried by a laterally slidabile bar 316 on a rack bar carriage 318 driven by a pinion 220 from a reversible electric motor (not shown). On the slide bar 316 is an upstanding pin 22 disposed to move in a cam groove or track 224. The cover actuating bar 138^a is pushed by the roller 314 incident to rack bar carriage actuation from the position of FIGURE 43 to that of FIGURE 44, shifting with it the cover 122 to the open position of FIGURE 44. By reversing the movement of the pinion 320 the rack bar carriage is restored to origin position at the left as indicated in FIGURE 43 at which time the pin 322 will enter an offset section of the cam groove 324 sufficient to withdraw the laterally slidabile bar 316 and the roller 314 from the path of the cover actuating bar 138^a.

Cylinder Cover Rotating Arm Actuation
FIGURES 45-49

Referring to FIGURES 45, 46 and 47, which represent the Load Station, 326 is a roller or finger on a rotating arm 328 mounted on a rotary shaft 330 driven by a reduction gear 332 from a reversible electric motor 334. The parts are all mounted on a suitable pedestal 336.

The actuation is similar to that illustrated in FIGURES 34-36 except that the contact roller 326 is mounted in an arm fast directly on the drive shaft of the speed reducer 332. The action of the rotating arm 328 and the roller 326 enclosing the cover 122 appears in FIGURES 46 and 47.

Referring more particularly to FIGURES 48 and 49 at the Unload Station, a similar mechanism is employed to move the cover 122 from the closed position of FIGURE 48 to the open position of FIGURE 49 with the uncovered opening 116 in the down discharge position. The actuating roller 338 which contacts the cover actuating arm 138^a is designated at 338 and its carrying rotating arm at 340, the latter being made fast to the shaft 342 driven by the reversible electric motor 344.

Loop Machine Adaptation
FIGURES 50-58

Referring in the first instance to FIGURES 50-54 inclusive, a cylinder receptacle 108^a is adapted to travel around in a closed loop. In this type machine there may be quite a number of the cylinders 108^a.

The cylinders 108^a are driven by sheaves or sprockets 152^a from belt or chain drives 154^a at both ends of the cylinders, such cylinders being supported in the belts or

chains 154^a and for this purpose the hangers 136^a are provided with slotted bearings 346.

A bolt 140^a and a nut 142^a serve to secure the cover actuating arm 138^a to a side segmental plate 126^a (FIGURE 55) of the cylinder cover 122^a. One or more cover latches 162^a are provided for securing the cover 122^a in open and closed positions. Cylinder stops 118^a and 120^a are provided at opposite sides of the cylinder opening 116^a to cooperate with a cover stop 124^a.

5 10 15 The cover actuating arm 138^a is arranged to contact a roller 348 at the Unload Station which roller is carried by a trip lever 350 on a shaft 352 to which is also affixed a trip arm 354 biased by a coil spring 356 down against an adjustable stop 358 (FIGURE 53). This trip arm 354 also normally depresses a wand 360 of a limit switch 362.

As the arm 138^a engages the roller 348 the cover will be arrested (FIGURE 50) following which the arm 138^a will depress the roller 348 (FIGURE 51) thus lifting the trip arm 354 (FIGURE 53) off its stop 358 and expanding the spring 356; at the same time the trip arm 354 releases the wand 360 and permits operation of the limit switch 362 to open the circuit of the cylinder rotating motor.

20 25 30 After the arm 138^a clears the roller 348 (FIGURE 52), the coil spring 356 (FIGURE 53) will draw the trip arm 354 down against its stop 358 and will again deactivate the limit switch 362 by depressing its wand 360. The trip lever 350 and its roller 348 will be correspondingly elevated into the path of the cover actuating arm 138^a of the next cylinder in line.

35 By timer or other arrangement, after the cylinder has been unloaded the same will be conveyed to a Loading Station for recharging and subsequent re-cycling.

35 40 45 FIGURES 54-58 inclusive, illustrate the cover closing device and allied mechanism. In these figures 364 represents a roller in the path of the cover actuating arm 138^a, such roller being mounted upon a trip lever 366 mounted on a rotary shaft 368 to which is also affixed a trip arm 370. A coil spring 372 attached to the trip arm 370 and to a part of the framework pulls the trip arm up against a stop 376. When the trip arm 370 is depressed as by raising of the roller 364 and lever 366, its tail lug 371 is raised releasing the wand 375 of a limit switch 379.

50 55 60 A main lever 378 is pivoted at 380 on the framework at the Loading Station just in advance of the roller 364. The lever 378 has arms 378^a and 378^b which pivot loosely about the pivot pin 380. A spring 382 is connected to a rear extension 378^c of upper lever arm 378^a and to an anchor member 388 on the frame of the machine. This spring 382 biases the lever 378 to the position of FIGURE 58 in which a stop 390 of lever 378 abuts a stop 392 projecting forwardly from a sleeve 394 loosely pivoted about pivot pin 380 between the lever arms 378^a and 378^b and rotatable independently of the lever 378.

65 70 75 A spring 384 is connected to rear arm 396 of sleeve 394 and to a fixed member 398 on the machine for biasing the rear arm 396 to a position against the stop 400. A wand 402 of the limit switch 386 is in engagement with the rear arm 396. The sleeve 394, its stop 392 and rear arm 396 together constitute a supplemental lever.

In operation, as the cylinder moves into the station its cover arm 138^a may be in such position as to strike the approaching or front side of lever 378, that is, the side opposite the spring 382, and in this event the lever 378 will yield, its stop 390 moving away from the sleeve stop 392 as the lever 378 rotates about the pivot 380 while expanding the spring 382. As the spring 384 is superior in load value to spring 382, the contracting effect of spring 382 on stop 390 against stop 392 will be negative.

Incident to its rotation, the cover arm 138^a will pass about or beneath the lever 378 and rotate backward against the rear side of lever 378 causing such lever 378 to rotate about the axis 380 in a direction to maintain engagement of the stops 390, 392 and thereby to rotate

the sleeve 394, the rear sleeve arm 396 and distend the overriding spring 384. In this motion the rear arm 396 rotates away from the stop 400 and pushes upon the wand 402 to open or close limit switch 386 which stops barrel rotation for loading.

Upon completion of the loading, the cylinder is then moved forward and the arm 138^a engages roller 364 and closes the cover. Upon completion of closing of the cover further motion of the arm 138^a against the roller 364 will cause the lever 366 to be rocked about its pivot, distending spring 372 and actuating limit switch 374 signalling the machine control circuitry that the thus loaded barrel is ready for movement to the first treatment station.

Although we have disclosed herein the best forms of the invention known to us at this time, we reserve the right to all such modifications and changes as may come within the scope of the following claims.

What is claimed is:

1. In combination, a cylindrical receptacle member having a loading and discharge opening in the side wall thereof, a cover member for the opening, said members relatively movable to open and close the opening, actuating means for moving the movable one of the members, and stop means for arresting the movement of the other member while the movement of the movable member continues so as to open and close the opening of said receptacle.

2. In combination, a cylindrical receptacle member having a loading and discharge opening in the side wall thereof, a cover member for the opening, said members relatively movable to open and close the opening, actuating means for moving the movable one of the members, entrainment means for yieldably entraining the other member to normally move with the one member, and stop means for arresting the movement of the other member while the movement of the movable member continues so as to open or close the opening of said receptacle.

3. In combination, a cylindrical receptacle member having a loading and discharge opening in the side wall thereof, a cover member for the opening, said members relatively movable to open and close the opening, actuating means for moving the movable one of the members, stop means for arresting the movement of the other member while the movement of the movable member continues so as to open or close the opening of said receptacle, and means for controlling the actuating means to cause the opening to arrive at a down position when the cover is opened.

4. In combination, a cylindrical receptacle member having a loading and discharge opening in the side wall thereof, a cover member for the opening, said members relatively movable to open and close the opening, actuating means for moving the movable one of the members, stop means for arresting the movement of the other member while the movement of the movable member continues so as to open or close the opening of said receptacle, and means for moving the receptacle member, after unloading, to a loading position with its opening in an upper location.

5. In combination, a cylindrical receptacle member having a loading and discharge opening in the side wall thereof, a cover member for the opening, said members relatively movable to open and close the opening, actuating means for moving the movable one of the members, stop means for arresting the movement of the other member while the movement of the movable member continues so as to open or close the opening of said receptacle, and means to suspend the operation of the actuating means when the opening is in unloading position.

6. The combination of claim 5 further comprising means to cause resumption of the operation of the actuating means after an interval for dumping to shift the opening from an unloading to a loading position and

thereupon again to discontinue operation of the actuating means pending loading.

7. In combination, a cylindrical receptacle member having a loading and discharge opening in the side wall thereof, a cover member for the opening, said members relatively movable to open and close the opening, actuating means for moving the movable one of the members, stop means for arresting the movement of the other member while the movement of the movable member continues so as to open or close the opening of said receptacle, and stop means between the members for arresting the relative movement of the members in the opened and closed positions of the cover member.

8. In combination, a horizontally mounted rotary cylindrical receptacle member having a loading and discharge opening in the side wall thereof, an arcuate cover member for the opening slidably fitted to the receptacle member, means for rotating the receptacle member and normally carrying around therewith the cover member, and stop means for arresting the movement of the cover member while the movement of the receptacle member continues so as to open or close the cover member.

9. The combination of claim 8 further comprising yieldable detent means between the cover and receptacle members positioned to be engaged in both open and closed positions of the cover.

10. The combination of claim 8 further comprising yieldable spring detent means carried by the receptacle at both sides of the opening, and a complementary detent member carried by the cover for automatically engaging the spring detent means in both open and closed positions of the cover.

11. In a machine of the kind described, a horizontally disposed tubular receptacle having a loading and discharge opening in the side wall thereof, a cover carried movably by the receptacle for uncovering and closing the opening, rotating means for rotating the receptacle, stops between the receptacle and cover engageable in the open and closed positions of the cover for causing rotary entrainment of the cover with the receptacle, a trip member carried externally by said receptacle relatively rotatable thereto and affixed to said cover, and a trigger member mounted on the machine in the path of the trip member for engagement to arrest movement of the cover while the receptacle continues to rotate to either open or close the opening.

12. A machine as claimed in claim 11 in which the trigger member is movably carried by the machine and is subject to yieldable load means for holding the same immovably against the trip member during opening or closing movement of the cover, said load means being overcome by the entrainment of the cover with the receptacle to permit the trigger member to have movement derived from the trip member, and means positioned to be actuated by the moved trigger member for shifting the receptacle away from the trigger member.

13. A machine as claimed in claim 11 further comprising a loading station at which the trigger member is movably mounted, yieldable load means imposed on said trigger to retain the same against movement by the trip member and to hold the trip member immovable until rotary movement of the receptacle through an angular distance sufficient to close the cover, the load means having a value less than the force of the rotary drive means for the receptacle and thereupon yielding to permit the trigger member to be moved by the entrained trip member, and means actuated by the moved trigger member to set the receptacle in motion away from the trigger member.

14. A machine as claimed in claim 11 further comprising an unload station on the machine at which the trigger member is movably mounted, yieldable load means imposed on the trigger member for holding the same and the trip member against movement until the opening is uncovered in a down discharge position, said load

means yielding to the superior force of the trip member when said trip member and the cover are entrained to rotate with the receptacle whereby the trip member is moved, means positioned to be actuated by the moved trip member to reverse rotation of the receptacle, after discharge, to bring the uncovered opening to an upper loading position, and means for thereupon discontinuing rotation of the receptacle.

15. A machine as claimed in claim 11 in which load and unload stations each contain trigger members movably mounted, and said trip member comprises long and short radial arms, the trigger member at one station being located without the radial range of the short arm and engageable only by the long arm, yieldable load means imposed on said trigger members for holding the trigger members against movement until the cover is closed at the load station and opened at the unload station whereupon the rotary entrained trip member will cause movement of the respective trigger members, means actuated by the trigger member at the load station to move the receptacle away from the load station and toward the unload station, means at the unload station positioned to be actuated by the moved trigger member to cause reversal of rotation of the receptacle, after discharge, to bring the uncovered opening to an upper load position, and means positioned to be actuated by the trip member at the unload station to thereupon discontinue rotation of the receptacle and return same to the load station.

16. In combination, a horizontally disposed cylindrical receptacle member having a loading and discharge opening, a cover member for the opening, said members relatively movable to uncover and close the opening, a cover arm fast with the cover member and movable with the cover member relatively to the receptacle to uncover and close the opening, and means positioned to act upon said cover arm to move the same to open and close the cover.

17. The combination of claim 16 in which the last-named means is a fluid pressure actuated motor having a plunger adapted to engage the cover arm.

18. The combination of claim 16 in which said last-named means is a rotating member having a projection in the path of the cover arm.

19. The combination of claim 16 in which said last-named means is a sprocket having a pin laterally projecting therefrom in the path of the cover arm, and a chain drive for rotating said sprocket.

20. The combination of claim 16 in which said means comprises a drive member movable into and out of the path of the cover arm, means to move the drive member in a direction to actuate the cover arm in opening and closing the cover, and means for laterally shifting said drive member out of the path of movement of the cover arm to permit the same to pass the drive member.

21. The combination of claim 20 in which the means for laterally shifting the drive member comprises a complementary pin and a cam slot.

22. The combination of claim 20 in which the means for moving the drive member to open and close the cover is a rack bar carriage having a lateral guideway for said drive member, and a pinion drive to the rack bar.

23. The combination of claim 16 in which said last-named means is a rotating arm having a part in the path of movement of said cover arm for engaging the cover arm and moving the same to correspondingly move the cover, and a motor for driving said rotating arm.

24. The combination of claim 23 in which said motor is a reversible electric motor and the rotating arm and cover arm are mounted for rotation with the rotating arm adapted to be rotated clockwise or anti-clockwise.

25. In a machine of the character described, a rotary receptacle having a loading and discharge opening, a cover movable back and forth to open and close the cover, rotary means for rotating the receptacle, a cover arm fast with the cover and relatively movable therewith with respect to rotation movement of the receptacle, a

stop lever on the machine having a part in the path of the cover arm, yieldable means connected to said stop lever to initially oppose rotary movement of the cover arm and cover while the receptacle rotates to open and close the cover but which yields on full closing or full opening of the cover, the relation of said cover arm and stop lever being such that when the cover arm is entrained to rotate with the receptacle such cover arm will depress the stop lever and distend the yieldable means, and a limit switch associated with the stop lever to be actuated thereby in the depressed position of the stop lever.

26. A machine as claimed in claim 25 further comprising an arm pivotally movable with the stop lever and connected to the yieldable means which is a spring biasing the stop lever to an elevated position, said limit switch having a wand normally engaged by said last-named arm and released thereby when the last-named arm is raised incident to the depressing of the stop lever.

27. In a machine of the character described, a receptacle having a loading and discharge opening, a cover movable relatively to the receptacle to uncover and close the opening, rotary means for rotating the receptacle, a cover arm fast to the cover and exposed on the exterior of the receptacle, a stop lever spring biased to a position in the path of the cover arm to initially arrest rotary movement of the cover arm until the load of the spring bias is overcome, conveying means for moving the receptacle bodily in a substantially horizontal direction, a conveying arresting lever positioned relatively to the stop lever to be engaged by the cover arm prior to its engagement with the stop lever, means for yieldably retaining said conveying arresting lever in a neutral position in the path of the cover arm, and a switch positioned to be actuated by said conveying arresting lever when the latter is rocked by the cover arm.

28. In a machine of the character described, a rotary and bodily movable receptacle having a loading and discharge opening, a cover movable relative to the receptacle for uncovering and closing the opening, a cover arm fast with the cover and also relatively rotatable with respect to the receptacle, rotary means applied to rotate the receptacle, conveying means applied to bodily move the receptacle, means positioned to engage the cover arm for de-activating the bodily movement of the receptacle, means adjacent the last-named means for engaging the cover arm to initially close the cover and subsequently to signal the conveying means to move the receptacle on to the treatment stations.

29. In a machine of the kind described in which a rotary work carrier is loaded and discharged and moved through pre-selected treatment stations, the carrier having a movable cover for closing and uncovering a filling and discharge opening, with an operating arm connected to the cover, mechanism for controlling the said closing and uncovering of the opening through the said arm comprising movable means on the machine positioned to be encountered by the arm and moved thereby in relatively opposite directions in one of which the arm passes idly by said means, and a limit switch positioned to be actuated by the means on movement in the other direction.

30. The mechanism of claim 29 in which said means is a main lever swiveled to rotate in opposite directions, a supplemental lever swiveled to rotate with respect to the main lever, separable stop means between the levers for entraining them for movement together in one rotary sense only, and yieldable means for biasing the levers to a position with the stops engaged.

31. The mechanism of claim 29 further comprising a second movable means on the machine spaced from the first means and in the path of said arm to be moved by the arm, and a second limit switch positioned to be actuated by said second means.
